US0D1039690S

(12) **United States Design Patent** (10) **Patent No.:** **US D1,039,690 S**
(45) **Date of Patent:** **** Aug. 20, 2024**

(54) **TAMPON**

(71) Applicant: **Tampro Inc.**, San Francisco, CA (US)

(72) Inventors: **Greta Catherine Meyer**, San Francisco, CA (US); **Amanda Paige Calabrese**, San Francisco, CA (US); **Elijah John Sampson Zenger**, New York, NY (US)

(73) Assignee: **Tampro Inc.**, San Francisco, CA (US)

(**) Term: **15 Years**

(21) Appl. No.: **29/748,907**

(22) Filed: **Sep. 1, 2020**

(51) **LOC (14) Cl.** **24-02**

(52) **U.S. Cl.**

USPC **D24/141**

(58) **Field of Classification Search**

(57) **CLAIM**

The ornamental design for a tampon, as shown and described.

DESCRIPTION

FIG. 1 is a top front perspective view of a tampon showing our design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

Broken lines shown in the drawings represent portions of the tampon that form no part of the claimed design.

1 Claim, 4 Drawing Sheets
